HUNT AND LAG PREVENTING MEANS

Bruno A. Wittkuhns, Summit, N. J., assignor to
Sperry Gyroscope Company, Inc., Brooklyn,
N. Y., a corporation of New York

Application February 7, 1933, Serial No. 655,544

4 Claims. (Cl. 74—7)

This invention relates to devices for transmitting the major rotary movements of a shaft subject to hunting or rapid oscillations of relatively small amplitude without introducing any lag in the major transmitted movements. Thus in the gyroscopic compass art the follow-up element on the compass continually hunts or oscillates through a small angle (on the order of a degree or two) and it is desired to transmit the major turning movements of this element without transmitting the hunt so that the repeater compasses only show the average position of the compass. The hunt is especially objectionable where the compass readings are magnified by coarse and fine repeater compasses. In the past this has been accomplished by a lost motion device which, although moderately successful in eliminating the hunt, introduces a lag when the ship is turning so that the transmitted reading is in error during that period. By my invention I have succeeded in eliminating the hunt without introducing lag.

Referring to the drawing illustrating several forms the invention may assume:

25 Fig. 1 shows my invention as applied to a gyro compass.

Fig. 2 illustrates a simplified form of the invention for use as a transmitting device between any driving and driven shaft.

30 Fig. 3 are two diagrams showing how lag is introduced by an ordinary lost motion device.

The reason why lag is introduced by a lost motion device may be appreciated by reference to Fig. 3 in which a pin P is mounted on the driving or actuating oscillatory member and the driven member is shown as a plate L having a slot S therein of the length equal to or slightly greater than the normal oscillatory movements of the pin. As long as the pin is merely oscillating, therefore, the plate L will occupy a central position with the index I opposite the average position of the pin. Now suppose that the pin P is given a translatory motion to the right superimposed on its oscillatory motion and of about the same rate. The pin then will move in that direction in a series of jumps but the average position of the plate L will no longer be centralized with respect to the pin but will lag behind the same a distance approximately equal to one half of the length of the slot S as long as the pin is so translating. As soon, however, as this translatory motion stops, the position of the plate will again be centralized. Therefore, the lag is only present during translation of the plate or, in other words,

in a gyro compass the lag in the transmission system will only be present during turning of the ship.

The elements of my invention are shown in Fig. 2 in which the driving oscillatory shaft is shown at 1 and the driven shaft at 2. Between the two shafts is placed a suitable form of differential gearing 3, said gearing in Fig. 2 being shown as of the bevel gear type. The planetary arm 4 of said gear train is connected to and turned from the shaft 1. Another arm 5 of said train is connected to one portion 6 of a lost motion device 12 connecting the same to said driving shaft 1. Said device is shown as comprising a pair of cones 7 mounted on a collar 8 pinned to shaft 1 and partially entering cone-shaped recesses 8' in member 6, thereby providing a lost motion between the cones and the recesses which may be adjusted in amount by raising or lowering the collar 8 on shaft 8¹. A light friction brake 9 is yieldingly held against the periphery of member 6 by spring 10 to hold this arm of the differential, unless positively turned. The third or driven arm 11 of said train drives the driven shaft 2 through a similar lost motion connection, said connection being shown in the form of a pair of cones 41 on member 11 which partially enter cone-shaped recesses 42 in a collar 13 on shaft 2, said collar likewise being provided with a spring-pressed friction brake 14.

To understand the theory of operation, let us suppose that the lost motion or play in the two devices is equal and that the amount of play in the lower lost motion device 12 is about twice that of the normal extent of oscillation of the cones 7. As the shaft 1 oscillates through this angle, the part 6 will not be moved and since it is held by a brake 9 the turning of the planetary arm through the same angle will rotate the arm 11 through double that angle. Therefore, if the same amount of play is allowed in the device 40 as in 12, the pins 41 will be oscillated to just touch the walls of the recesses during the normal hunting action but not to move the same. Now suppose that shaft 1 is turned in one direction through sufficient distance to contact cones 7 with depressions 8' but without moving the same. This motion will obviously turn the member 11 through twice this distance which, therefore, moves the shaft 2 through an angle equal to the movement of the cones to one side of central, or in other words, equal to the lost motion on one side, thereby compensating at once for the entire lag. Assuming then the shaft 1 to keep turning in that direction, a further movement of the 110

shaft will carry part 6 with it and, therefore, all parts of the differential will turn together at the same speed and shafts 1 and 2 will move together with shaft 2 advanced enough to compensate for the lag. In other words, at the beginning of this translatory motion, the shaft 2 has been advanced an amount equal to the lag which would otherwise be introduced by the lost motion connection during such translatory motion. It is 10 obvious that by varying the amounts of lost motion between the cones and recesses or by altering the differential gear ratios that a greater or less advance of the shaft 2 may be obtained for compensating for lost motion in other parts of 15 the transmission system, or for varying relative speeds of hunting and major rotation.

Fig. 1 illustrates how my invention may be applied to a gyro compass or similar device between the hunting follow-up element and the electrical 20 transmitter which transmits the position of the compass to the repeater compasses. The sensitive element of the compass is shown at 20, the follow-up element 21 being actuated therefrom by means such as the follow-up contacts 22-23 25 which actuate the azimuth motor 24 to turn the large gear 25 on the follow-up element. The usual compass card 26 may be mounted on the follow-up element and there is also shown a gear 27 thereon for turning the transmitter 28. Between 30 said gear and transmitter, I interpose my lost motion devices. As shown, the driving shaft 1', in this instance, is turned through step-up gearing 29, 30 from the gear 27, the gear 30 meshing with a pinion 31 which is secured to shaft 1' 35 and which carries the lost motion cones 7'. Pinion 31 is shown as secured to a sleeve 33 which is slidably but non-rotatably mounted on shaft 1'. For adjusting said sleeve to vary the amount of lost motion, I have shown a nut 32 threaded on 40 the lower end of the shaft 1' and normally locked in place by the lock nut 34. Obviously, by loosening the lock nut and turning the nut the sleeve may be moved up and down on the shaft 1' to raise and lower the cones to vary the lost motion. Said cones engage conical openings 8' in 45 the member 6' which may also be provided with a brake 9'.

As before, the shaft 1' turns the planetary or differential arm 4' of the differential gear train 50 3', the train in this instance being shown as of the spur gear type. The lower arm of said train comprises a pinion 5' which is secured to the member 6', while the upper or driven member 11' is formed by the spur pinion 35 to which is 55 secured a cup-like annular gear 37 meshing with gear 38, which may be axially adjustable by nut 44 as in the case of pinion 31. Gear 38 carries the cones 41' of the second lost motion device 40', the apertured disc 13' in this instance being 60 secured directly to the driven shaft 2' of the transmitter 28, the brake being shown at 47. A repeater card 48 is shown mounted on the shaft of the transmitter which is read in connection with the index 49. In this case the repeater card 65 is of the "fine" variety, that is, for one revolu-

tion of the compass the repeater card rotates a number of revolutions, say 36, so as to give magnified compass readings. With such fine reading compass cards, it is highly important that all lost motion and lag be eliminated since the readings are magnified 36 to 1 on the repeater card.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. In a lost motion device for eliminating hunt without lag comprising a driving hunting shaft, a driven non-hunting shaft, a pair of lost motion devices between said shafts, each device having a driving and driven part and a differential gearing between said devices, one arm of which is driven by said driving shaft, another arm by the driven part of the first device, and a third arm driving the driving part of the second device, the driven part thereof driving said driven shaft.

2. A lost motion device as claimed in claim 1 for driving shafts subject to an oscillation of limited extent in which the driving shaft turns the planetary arm of said differential gear train and in which the lost motion in the first device is double the limited extent of oscillation of the driving shaft.

3. In a lost motion device for gyro compasses and the like, the combination with the follow-up hunting element and a high speed transmitter, of step-up gearing between the same, a pair of lost motion devices in said gearing connected in series, and a differential gear train having the planetary arm driven from said follow-up element, another arm from one of said devices and a third arm turning the other of said devices, said transmitter being driven from said last-named device.

4. In a lost motion device for gyro compasses and the like, the combination with the follow-up hunting element and a high speed transmitter, of step-up gearing between the same, a pair of lost motion devices in said gearing connected in series, a differential gear train having the planetary arm driven from said follow-up element, another arm from one of said devices, and a third arm turning the other of said devices, said transmitter being driven from said last-named device, and means for adjusting said devices to compensate for other lost motion or lag in the follow-up system.

BRUNO A. WITTKUHNS.
